(57) **CLAIM**

The ornamental design of a soccer shoe training cover, as shown and described.

DESCRIPTION

FIG. 1 is a top view of a soccer shoe training cover, showing my new design;

FIG. 2 is a right side view thereof;

FIG. 3 is a left side view thereof;

FIG. 4 is a bottom view thereof;

FIG. 5 is a front view thereof; and,

FIG. 6 is a rear view thereof.

The broken line showing of the shoe is included for the purpose illustrating environmental structure and forms no part of the claimed design.
